HACKSAW

Max Sultan, Brooklyn, N. Y.

Application January 25, 1940, Serial No. 315,496

2 Claims. (Cl. 145—108)

The object of the present invention is to provide a hacksaw comprising a novel form of holder and a blade especially designed to coact therewith, the two being so formed that the blade may be securely held in fixed position in each of six different mountings on the holder.

The invention will be described with reference to the accompanying drawing, in which:

Figure 1 is a view in side elevation of an embodiment of the invention.

Figure 2 is a top plan view of the embodiment shown in Figure 1.

Figure 3 is a sectional elevation taken on the line 3—3, Figure 1.

Figure 4 is an enlarged sectional view on the line 4—4, Figure 1.

Figure 5 is a view in elevation taken at one end of the clamping bolt.

Figure 6 is a view in elevation taken at one side of the clamping bolt.

Figure 7 is a fragmentary view of the hacksaw blade toward the rear end of the latter.

Figure 8 is a view in side elevation similar to Figure 1 and showing the blade mounted rearwardly of the clamping bolt.

Figure 9 is a view similar to Figure 2, the blade being mounted on the top of the holder.

Referring to the drawing, it will be seen that the holder comprises a primary member 1 carrying a handle 2 from which projects a finger piece 3 so that the handle and finger piece are preferably formed as a pistol grip. The primary member 1 is in the form of a vertical plate having centrally thereof and projected forwardly an integral web 1x. At the top of the web and extending on opposite sides thereof is a wall 4 and at the bottom of the web and extending at opposite sides thereof is a wall 4x.

The walls just described provide at each side of the web 1x a U-shaped channelway for the reception of the hacksaw blade.

At each side of the web 1x and somewhat rearwardly thereof is a hook lug 5. Also at each side of the web and projected from the walls 4, 4x, are opposed wedge lugs 6.

The walls 4, 4x, near the front ends thereof are formed with apertures to receive a clamping bolt 7, the bolt being threaded at its lower end to receive the wing nut 8. As shown more particularly in Figures 5 and 6, the clamping bolt is flat-sided and at the top of each side under the head of the bolt is a downwardly projected lug 7x having its inner wall tapered to provide a recess for the reception of the top of the blade.

The blade is shown at 9. Rearwardly of the

blade and adapted to lie in register with the clamping bolt, there is formed a bolt-receiving aperture 9x, preferably oval in form. Rearwardly of the oval aperture 9x the blade is formed with wedge-shaped recesses 10 to receive the lugs 6. Also toward the extreme rear of the blade the latter is formed with an aperture to receive one of the two hook shaped lugs 5.

When the wing nut 8 is turned toward its position shown in Figure 1 to release the clamping bolt 7, the latter may be moved upwardly until its lugs 7x clear the blade 9. The blade may then be removed by a lateral movement so that it will swing rearwardly and become disengaged from the hook 5. In restoring the blade to operative position, it is so placed that the hook 5 enters the rearmost blade aperture. The blade is then swung until it contacts with web 1x and in so doing the recesses 10 are entered by the lugs 6. In such movement the clamping nut is held in raised position so that the lugs 7x will lie above the blade. The clamping bolt is then moved downward to its position as shown in Figure 1 or Figure 3 and the wing nut 8 is turned, causing the bolt to descend and firmly clamp the blade between the appropriate lugs 7x and the wall 4x.

Inasmuch as the same blade-engaging elements are used on each side of the web 1x, the blade may be positioned either as shown in Figure 1 or Figure 8. Also, the blade may be reversed in position on either side of the web, which means that the saw blade would lie with its toothed edge uppermost. Thus with the use of the device as shown and described, the blade may be held in four positions. The fifth and sixth positions will now be described.

Referring to Figure 9, it will be seen that the hook 5x carried by the top wall 4, and the oval aperture 9x permits the blade to be positioned upon the top wall 4 and held in such position by the clamping action of the bolt. The bolt need not be removed. Preferably, its head is oval in shape so that when the bolt is turned the major axis of the head extending longitudinally of plate 4, the blade may receive hook 5x and the head of the bolt pass through the aperture 9x. Thereupon, the head of the bolt may be turned to the position shown in Figure 9 and the wing nut 8 actuated to clamp the blade firmly in position.

By means of the invention, my hacksaw is capable of such adjustment in the position of the blade that sawing operations otherwise difficult or impossible to perform, can be readily accom-

plished, and the means to that end are simple and inexpensively constructed.

Having described my invention, what I claim and desire to secure by Letters Patent, is as follows:

1. In a hacksaw, a holder comprising a primary member carrying a forwardly projecting web, plates carried by the web at its top and bottom and projecting laterally of both faces of the web, the plates projecting forwardly of the web, the projecting portions of the plates being formed with aligned apertures, lug projections carried by the web at each side thereof and a clamping bolt passing through the aligned apertures and having a blade engaging shoulder. 15

adapted to engage an edge of a blade in opposition to the bearing action upon the opposite edge of the blade provided by one of the plates.

2. A hacksaw constructed in accordance with claim 1, in which the bolt is rotatable to carry its blade clamping shoulder to either side of the holder, the bolt being formed at its top with an elliptical head, and a stud carried by that one of the plates which immediately supports the elliptical head of the bolt said head and stud being of such dimensions as to pass through a corresponding elliptical hole and aperture in a saw blade.

MAX SULTAN.
